US0D1026088S

(12) **United States Design Patent** (10) Patent No.: **US D1,026,088 S**
(45) Date of Patent: ** May 7, 2024

(54) **LABEL PRINTER**

(71) Applicant: **BROTHER INDUSTRIES, LTD.**,
Nagoya (JP)

(72) Inventors: **Kazuki Nakano**, Iwakura (JP); **Robin Riazi**, Komaki (JP); **Hiroki Tabuchi**, Nagoya (JP); **Masahide Asano**, Nagoya (JP)

(73) Assignee: **BROTHER INDUSTRIES, LTD.**,
Nagoya (JP)

(**) Term: **15 Years**

(21) Appl. No.: **29/898,451**

(22) Filed: **Jul. 27, 2023**

(30) **Foreign Application Priority Data**

Jan. 31, 2023 (JP) ..... 2023-001604 D

(51) **LOC (14) Cl.** **14-02**

(52) **U.S. Cl.**

USPC **D18/19**

(57) **CLAIM**

The ornamental design for a label printer, as shown and described.

DESCRIPTION

FIG. 1 is a perspective view of the label printer;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is a perspective view thereof in an alternative state. The evenly spaced broken lines depict unclaimed parts of the label printer and form no part of the claimed design.

1 Claim, 8 Drawing Sheets
